Attorney

UNITED STATES PATENT OFFICE.

ALFRED J. McMINN, OF DENVER, COLORADO.

SHADE HOLDER.

Application filed August 15, 1922. Serial No. 531,974.

To all whom it may concern:

Be it known that I, ALFRED J. McMINN, a citizen of the United States, residing at the city and county of Denver and State of Colorado, have invented certain new and useful Improvements in Shade Holders; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to shade holders and has special reference to a holder of the type employed in connection with electric fixtures.

It is the object of this invention to produce a shade holder that is so constructed that the shade can be conveniently removed therefrom and replaced therein.

I accomplish my object by means which I will describe in detail hereinafter and which consists broadly in forming the ring, which embraces the upper end of the shade, with a joint that can be quickly opened and closed.

In order to more clearly describe my invention, I shall have reference to the accompanying drawing in which—

Fig. 1 represents a side elevation of an electric lamp socket having a shade attached thereto by my improved holder, the upper part of the socket and the lower part of the shade being broken away.

Fig. 2 is a top plan view of my shade holder removed from the lamp;

Fig. 3 is a section taken on line 3—3, Fig. 2, and shows the means provided for engaging the bead on the shade;

Fig. 4 is a section taken on line 4—4, Fig. 2, and shows the construction of the lock; and

Fig. 5 is a section taken on line 5—5, Fig. 2.

The same reference numbers will be used to designate the same parts throughout the several views.

Numeral 1 represents a lamp socket of usual construction, having a bead 2 thereon, and 3 represents an ordinary incandescent lamp. In order to hold the shade 4 in position about the lamp, I provide a holder which consists of a central ring-like portion 5, which is open on one side and has its

outwardly projecting ends 6 connected by a screw 7 in the usual manner. A pair of diametrically spaced arms 8 joins the ring 5 to a larger shade holding ring 9, which is preferably of channel-like cross section and is provided on its lower side with three or more inwardly projecting fingers 10 whose function it is to engage in the annular groove of the shade 4 in the manner shown in Fig. 3.

The inner ends of fingers 10 are preferably upwardly and outwardly curved in the manner shown at 11 in Fig. 3, so as to conform more nearly to the curvature of the groove with which they cooperate. Ring 9 is cut and has its ends 12 and 13 overlapped in the manner shown in Fig. 2 and locked together by means which I will now describe. The end 12 is inwardly offset the thickness of the material as indicated by numeral 14 (Fig. 2) and is provided near its outer end with a pin 15 which is adapted to enter and engage with the hole 16 in end 13 and thereby locking the two ends against longitudinal movement. A slight inward pressure on end 12 at the point indicated by the arrows in Figs. 1 and 2 will remove the pin 15 from the hole 16 and permit the ends 12 and 13 to spread apart. In order to guide the pin 15 into the opening 16, I provide an outwardly pressed channeled 17 within which the point of the pin 15 slides when the ends are pressed together for the purpose of locking them. The ring 9 is preferably distorted slightly from the circular shape so that it will have a tendency to open, which tendency is resisted by the pin 15 engaging in the hole 16. I have shown only two arms 8, but I may employ three if I so desire, although two is considered to be sufficient for ordinary purposes.

The operation of my holder is as follows: The holder is firmly clamped in place on the socket by means of the clamping ring 5 and the screw 7 in the manner shown in Fig. 1. The lock that holds the ends 12 and 13 together is then opened and the upper grooved end of the shade 4 is inserted within the ring 9 in such a manner that the fingers 10 engage the groove in the manner shown in Fig. 3. The ends of the ring are then squeezed together until the pin 15 engages the opening 16, when the shade will be securely held in place. When it is desired to remove the shade end 12 is pressed inwardly until the pin 15 leaves the hole 16,

when the ends may be moved apart sufficiently to permit the shade to be removed.

From the above it will be apparent that I have provided a shade holder that is so 5 constructed and designed that the shade may be easily and quickly attached thereto or removed therefrom.

I desire to call particular attention to the fact that my invention resides in the 10 combination of a shade holder of a special construction and a snap lock for securing the ends of the shade holding ring. This type of lock is of great importance in a shade holder having a separate shade clamping ring 9. I do not desire to claim broadly a shade holder having a snap lock for 15 holding the shade therein, but rather this in combination with the other elements shown.

Having now described my invention, what 20 I claim as new is:

A shade holder consisting of a clamping ring adapted to encircle a lamp socket, means comprising a screw for clamping said ring to said socket, a shade-holder ring of greater diameter than the clamping ring, 25 means comprising a plurality of arms connecting the two rings, said shade-holder ring having a cut therein whereby two ends are provided, said ends overlapping each other and provided with a lock comprising a pin on one end and an opening in the other end, the end having the hole being provided with an outwardly pressed guideway for directing the pin into the hole, and inwardly projecting fingers carried by the lower edge 30 of the shade-holding ring for engaging and holding the shade.

In testimony whereof I affix my signature.

ALFRED J. McMINN.
